UNITED STATES PATENT OFFICE.

GEORGE SPIVAK, OF CHICAGO, ILLINOIS.

GLOVE.

1,179,572.

Specification of Letters Patent. Patented Apr. 18, 1916.

Application filed June 11, 1915. Serial No. 33,535.

To all whom it may concern:

Be it known that I, GEORGE SPIVAK, a subject of the Czar of Russia, residing at Chicago, in the county of Cook and State 5 of Illinois, have invented new and useful Improvements in Gloves, of which the following is a specification.

This invention relates to improvements in gloves.

10 An object of the invention is to economize in material and labor in the manufacture of gloves by providing a glove which is made of a main pattern or blank, preferably made of cut material and adapted to provide a 15 complete covering for several fingers of the hand and a partial covering for several other fingers, said main pattern being united with an additional pattern or blank which is adapted to supplement the said partial 20 finger covering of the main pattern. This method of cutting glove patterns and uniting the same may be used in connection with soft and pliable materials, although it is especially adapted for the manufacture of 25 working gloves from soft fabric. It has been found that with the average size of a man's working glove, in each pair of gloves a saving of six inches of material may be obtained, and that the cost of cutting and 30 sewing may also be considerably reduced.

With the objects of economizing in material and labor and with other objects in view, the improvements in the manufacture of gloves are described in the following 35 specification, and are pointed out in the appended claim; a glove pattern of the kind described being shown, by way of example, in the accompanying drawing.

In the drawing Figure 1 is a plan view 40 of the main pattern for a glove; Fig. 2 is a plan view of a supplementary plan or pattern which enters into the manufacture; Fig. 3 is a diagrammatic plan view of the two glove patterns in folded and partly 45 completed condition.

The main pattern of the glove, as shown in Fig. 1, is for the hand portion of the glove only, without the wrist portion of the same. The material is cut to provide a plurality of projections which, in the finished 50 glove, are adapted to form the complete or partial coverings for the various fingers of the hand. These finger portions are designated in the drawing by the numerals 1^a, 1^b; 2^a, 2^b, and so forth, indicating the front and back coverings respectively for the

thumb, the forefinger, and the other fingers of the hand.

The entire pattern may be folded along a straight line 10, extending from a point between the finger portions 5^a and 5^b, and being in the finished glove located at the side of the hand, whereby the covers 5^a and 5^b for the small finger are placed in registration with each other and may be sewed together along the lines 11 and 12, providing in this manner a complete covering for the small finger of the hand. It is to be noted in the description of the manufacture of this glove that the tendency is to locate the 60 seams for the various finger portions approximately on the sides of the fingers and to give said coverings an approximately circular cross-section, like in ordinary gloves, and that for this reason it may be necessary 65 to bend or fold certain of these finger portions longitudinally on themselves until the seams reach the position suitable for the manufacture of a complete glove. The finger portion 5^a is provided near its root with 70 a transverse slit having edges 13 and 13', the portion 5^a being folded against itself on a line 31 extending from the tip of the portion to the termination of the slit.

When the main pattern is folded along 75 the line 10, as previously stated, the inner thumb strip 1^b, shown at the right hand end of the pattern, will come approximately into registration with the outer thumb strip 1^a, which has been turned inwardly along 80 the line 14, as indicated in Fig. 1. The inner thumb strip 1^b, located between the outer strip 1^a and the rest of the pattern, is then folded about the line 15 in direction 85 toward the forefinger portion, completing 90 thereby the covering for the thumb. The outer strip 1^a may be folded against itself on the line 32, and the two strips 1^a and 1^b 95 may be sewed together on the edges 33 and 34.

The two forefinger portions 2^a and 2^b are folded toward each other along the line 15, whereby the two edges 16 and 17 of these portions are brought into registration to complete the covering for the forefinger, 100 the portion 2^a extending from a transverse slit with the edges 18 and 18', which slit is approximately in alinement with the slit 13 13' of the adjacent portion 5^a for the small finger.

In the folding of the pattern along the line 10 an approximately straight horizon-

tal edge 19 at the right hand end of the pattern, in opposition to the inner thumb strip 1^b, will be brought into approximate alinement with the edge 18' at the root of 5 the portion 2^b for the forefinger. The complete thumb portion and complete forefinger portion of the glove may then be sewed together on the edge 18', 19, while the two halves of the pattern folded on the line 10 10 are united furthermore along the edge portions 21 and 22, which have been brought into registration, by the folding operation. The forefinger portion 2^b being folded against the forefinger portion 2^a and 15 the edges 16 and 17 of these two portions being united while the straight edge 19 is also being connected with the lower straight edge 18' of the forefinger portion 2^b, and the portion 5^a being folded against the 20 small finger portion 5^b and being, furthermore, bent along a line which terminates at the end of the cut 13, a space is left between the completed forefinger and the completed small finger of the glove. The 25 partial cover portions 4^a and 3^a of the pattern will now be located in the space between said two complete finger portions, and in order to complete the entire glove it is only necessary to bring the smaller pattern 20, Fig. 2, into registration with the 30 said portions 3^a and 4^a, and, after suitable bending or folding the edges of the small pattern, to unite these edges of the portions 4^b and 3^b with the edges of 4^a and 3^a. The 35 width of the supplementary pattern 20 measured along the bottom edge 25 of the same may be somewhat larger than the combined width of the finger portions 4^a and 3^a, so that, in order to complete the covering for the third and fourth finger and 40 to give ample space for the same, the por-

tions 4^b and 3^b of the smaller pattern may be bent or folded over along the lines 26 and 27. The edge 25 of the smaller pattern is then, by sewing, united to the 45 straight edges 18, 13, and this smaller pattern 20 is also, by sewing, connected with the adjacent bottom edges 18' and 13' of the covering for the forefinger and for the small finger. After the hand portion of the 50 glove is prepared in the manner indicated above, a wrist portion (not shown) may be sewed on to the same, either made of the same material or of other material. It is also obvious that the pattern may directly 55 be provided with a suitable wrist portion (not shown in the drawing).

I claim:

As an article of manufacture, a glove made of a main blank comprising a back 60 portion which contains the outer portion of the thumb, a complete outer and part of the inner portion of the index finger and the outer portion of the little finger, said inner portion of the index finger having a 65 lower straight edge and abutting with its edge the adjacent edge of said outer portion of said little finger and a palm portion integral with the inner part of the little, ring and middle fingers, the inner 70 portion of the thumb, and part of the inner portion of the index finger, said inner portion of the index finger having an upper straight edge in substantial alinement with the straight edge of the complementary 75 inner portion of the index finger and a secondary blank shaped to form the supplementary outer parts for the ring and middle fingers.

In testimony whereof I affix my signature.

GEORGE SPIVAK.
